CLAIM

The ornamental design for a part of shoulder strap, as shown and described.

DESCRIPTION

1. Part of shoulder strap

FIG. 1.1 is a perspective view of a part of shoulder strap, showing our design;

FIG. 1.2 is a front elevation view thereof;

FIG. 1.3 is a side elevation view thereof;

FIG. 1.4 is an enlarged view thereof;

FIG. 1.5 is another enlarged view thereof;

FIG. 1.6 is another enlarged view thereof; and

FIG. 1.7 is another enlarged perspective view thereof.
